UNITED STATES PATENT OFFICE.

WILLIAM G. LYONS, OF LA CROSSE, WISCONSIN.

WIRE-STRETCHING TOOL.

Application filed January 3, 1922. Serial No. 526,306.

To all whom it may concern:

Be it known that I, WILLIAM G. LYONS, a citizen of the United States, and a resident of La Crosse, in the county of La 5 Crosse and State of Wisconsin, have invented certain new and useful Improvements in a Wire-Stretching Tool, of which the following is a specification.

My invention relates to wire stretching 10 tools and is designed particularly to enable wire screen, screen cloth or other like material to be fastened onto frames, casements or the like and the material stretched while it is applied.

15 This invention is distinguished by its simplicity and efficiency, it being cheap to manufacture and particularly adaptable to the use for which it is designed.

In brief my invention comprises a metal 20 or wood handle into the working end of which are set a plurality of metal studs arranged in a plane with the axis of the handle, these studs being of graduated length, with the shortest of the studs at one 25 end and the longest at the other. The length of the studs increases by a constant quantity, which feature is of particular advantage as will be explained more fully hereinafter.

30 The manner in which my device is used and the many advantages thereof will be made more apparent in the accompanying specification and drawings in which:

Fig. 1 is a perspective view of my improved tool in the operation of stretching 35 the wire screen,

Fig. 2 is a similar view with the tool shown in a different position,

Fig. 3 is a side elevation of the tool,

40 Fig. 4 is a side elevation as viewed from the left in Fig. 3, and

Fig. 5 is a bottom plan view.

Referring now more particularly to the drawings it will be seen that the tool consists of a handle 10 which may be of wood, metal or any suitable material and is formed with what will be termed a head 11. Projecting from this head 11 in a plane with the axis of the handle is a plurality of metal 45 studs or pins 12. The projecting ends of these studs are beveled on each side to form chisel edges 13. It should furthermore be noted that these studs are of graduated lengths, the shortest stud being to the left 50 as viewed in Fig. 3, the length thereof increasing by a constant quantity toward the

right, the chisel edges being inclined parallel to a line drawn from the shortest stud to the longest stud. It should furthermore be noted that the studs are disposed one behind the other in a single plane. 60

For the purpose of describing the method of operation there is illustrated for example a frame 14 upon which there is to be fastened a screen cloth 15. The screen cloth 65 is first tacked along two of its edges as clearly illustrated. Thereupon, commencing at the corner formed by a fastened and an unfastened edge the tool is inserted through the screen cloth and into the material of the frame or casing to which the screen cloth is to be fastened. The tool is inserted with the shortest of the studs toward the fastened edge as clearly illustrated in Fig. 1, and with the plane of the 70 studs parallel to the edge about to be fastened. The axis of the handle is inclined toward the corner of the two fastened edges. That is, the handle is at an acute angle with the plane of the screen cloth as laid 75 upon the frame and is inclined towards the corner A of the frame (see Fig. 1).

As has heretofore been stated, the studs have passed through the screen cloth and are engaged with their chisel edges into the 80 frame. The handle of the tool is then raised to the vertical position relatively to the plane of the screen cloth as laid upon the frame, by which operation the studs engage the meshes of the screen cloth through which 85 they have been inserted and stretch the screen cloth away from both edges and hold the same taut whereupon the screen is tacked or fastened to the frame as far as the same is stretched by this first operation. The position of the tool after it has been raised to a vertical position is illustrated in Fig. 2. The tool is then disengaged and re-inserted 90 progressively along this unfastened edge and the fourth side of the frame until the screen 95 is stretched and fastened along all sides. 100

Obviously by inclining the tool toward the corner of the frame designated A in Fig. 1 and thereafter raising the same vertically, the wire is stretched cross-wise of the frame 105 while the provision of studs of graduated length disposed parallel to the length of the frame, stretches the screen cloth lengthwise. Furthermore, the studs will be caused to successively disengage the screen cloth as 110 the handle is moved in a direction corresponding to the length of the frame, that is,

in a direction whereupon the shortest stud first disengages the screen cloth and each stud successively disengages the screen cloth until finally only the longest stud is in engagement with the frame and the screen cloth.

By forming the active ends of the studs with chisel edges the studs are caused to have a firm engagement with the frame or 10 casing to which the screen is to be fastened and do not scratch or mar the wood or other material of the frame.

Obviously the number of studs may be varied as may also the length of the same and 15 the relative difference of length of the several studs. To this end I reserve the right to make this or any other modification in the specific structure illustrated as may come 20 within the purview of the accompanying claims.

Having thus described my invention, what I claim is:

1. A stretching tool of the class described comprising a handle, a plurality of studs of 25 graduated length projecting from said handle, said studs being formed with chisel

edges, said studs being adapted to be disposed at an angle projecting through the material to be stretched and into the frame upon which the material is to be attached, 30 said material being stretched by moving said handle to a vertical position relatively to the plane of the material as laid upon the frame.

2. In a tool for stretching screen cloth upon a frame or the like, a handle, a plurality of studs rigidly secured to said handle and projecting therefrom in a plane with the axis of said handle, said studs being of graduated length, successively arranged and in 35 a row, said studs being formed with chisel edges, whereby said studs may be inserted through the screen cloth into the frame, with the edges of said studs parallel to the side of the frame and the handle inclined at an acute angle relative to the plane of the screen cloth as laid upon the frame and said screen cloth stretched by moving said handle to a vertical position relative to said screen cloth and successively disengaging said studs from 40 said frame and said screen cloth.

WILLIAM G. LYONS.
